UNITED STATES PATENT OFFICE

ROYAL A. CLAPP, OF BROOKLINE, MASSACHUSETTS

MOTION PICTURE PROJECTING MACHINE

Application filed December 10, 1927. Serial No. 239,175.

My present invention relates to machines for projecting pictures from continuous strips of films, otherwise known as moving picture projecting machines.

5 An important object of the present invention is to devise a machine which will have a minimum number of parts, and which will, therefore, be economical to manufacture, easy to assemble, and simple to operate.

10 Also, by reducing the number of parts utilized in the construction and operation of the machine, a much lighter and more compact apparatus is produced than would otherwise be possible, enabling the same to be handled 15 more easily and to be utilized in installations where a larger machine would be unwieldy and impractical.

A further object of the present invention resides in the provision of means, utilized to 20 advance the film in an intermittent motion, which means will be provided with a slow start, a smooth acceleration, and a quick stop. I accomplish this desirable result by means of an improved Geneva movement, in which 25 I substitute, for the four radial slots heretofore utilized, four curved slots or cam paths. In this manner, the pin or roller carried by the driving wheel will enter said slots and engage the same on the curved side of each 30 slot in succession. This will eliminate the annoying click which has heretofore been present in standard Geneva movements, and will also result in imparting a slow start to the rotation of the driven wheel, will give 35 a smooth acceleration thereto, while the driven wheel will be brought to an instant stop at the proper moment. In this manner, I am enabled to increase the ratio of the 40 driving and driven wheels from three to one, to five or six to one, or to a still further degree if desired. This ratio of five or six to one is desirable, and in fact necessary in moving picture projectors, due to the speed with 45 which the film must be fed through the camera. With the standard Geneva movement it has heretofore been impossible to obtain this ratio resulting in fast feeding, except with the disadvantages above explained, but by my novel invention the same

is accomplished in an extremely efficient manner.

A further feature of the present invention resides in so mounting the driven wheel of the Geneva movement, and the film feeding 55 means controlled thereby, that any wear may be readily compensated for, thus increasing the life of the machine, and enabling a smooth, silent operation thereof at all times.

A further object of the invention is to 60 provide novel means for holding the film against the feeding sprockets. I accomplish this in such manner that only the outer edges of the film, adjacent to the perforations provided for the sprocket teeth, will be engaged 65 by the holding means, leaving the center of the film unengaged, thus eliminating any scratching or marring of the film against the sprockets or other feeding means. I accomplish this desirable result by providing a 70 pivoted frame or holder, at one end of which is pivotally mounted a shoe having thereon two upright yokes or pairs of webs having concave film and sprocket engaging surfaces. Into the yokes will project the teeth 75 of the sprockets, the concave surfaces of the yokes or webs holding the film at each side of each line of perforations, but leaving the center of the film free of any holding devices. Also, by having the above mentioned shoe 80 pivoted in the pivoted frame, the concave surfaces in said yokes or webs will follow the sprocket to any position to which it, together with the driven Geneva wheel, may be moved.

The above and further features of the invention, details of construction, combinations of parts and advantages, will be hereinafter more fully pointed out and claimed.

Referring to the drawings, illustrating preferred embodiments of the present invention,

Fig. 1 is a side elevation of my novel moving picture projecting machine;

Fig. 2 is a cross-sectional view on the line 2—2 of Fig. 4;

Fig. 3 is a cross-sectional view on the line 3—3 of Fig. 4;

Fig. 4 is a cross-sectional view on the line 4—4 of Fig. 9;

Fig. 5 is a detail view, on an enlarged scale, 100

of my novel and improved Geneva movement;

Fig. 6 is a cross-sectional view on the line 6—6 of Fig. 1;

Fig. 7 is a cross-sectional view on the line 5 7—7 of Fig. 1;

Fig. 8 is a perspective of the spring member to hold the film against the aperture;

Fig. 9 is a top plan view of the machine; 10 and

Fig. 10 is a perspective view, on an enlarged scale, of my novel film holding device.

Referring now to the drawings for a detailed description of the machine and its 15 operation, 11 designates the base of the machine, resting on legs 12 at one end, and on an adjustable screw 13 at the other end. This adjustable screw is controlled by a wing nut 14, or other suitable device, to raise or lower that end of the base on which is mounted the lamp house 15. Within the house 15 is located a bulb 16 and at one side of said house is provided an aperture 17 through which the light from the bulb 16 will project.

The base 11 is provided with a vertical wall 18 in which is positioned a condenser lens 19. Affixed to the wall 18 by screws 20 is a housing 21 within which is secured a reflector or mirror 22 fixed at an angle of 45° to the wall 18. The condenser 19 is alined with the aperture 17 in the lamp house 15, so that the light from the bulb will project through the condenser, striking against the reflector 22 and being deflected therefrom toward the front 25 of the machine, through the apertures 23 and 24 in the plates 25 and 26 respectively, and thence through the lens 36 in the lens barrel 27 to the screen on which the picture is to be displayed. The plate 25 has a flange 28 secured to the wall 18 by screws 29. Affixed to the plate 26 by screws 30 is a flange 31 of a spring plate or member 32 illustrated in detail in Fig. 8. This spring 32 has a pair of legs 33 spanning the aperture 23, said 35 spring being pressed against the inner surface of the wall or plate 25, the legs 33 being then bent at right angles as at 34 and provided at their ends with upturned lips 35 adapted to engage the inner surface of the 50 plate 26 to provide an increased pressure of the spring 32 against the inner surface of the wall 25. The plate 26 is pivotally mounted on a pin 37 and is held in normal position, as in Fig. 3, by a spring 38. This spring 38 55 also assists in holding the spring 32 against the inner surface of the plate 25 in a firm manner. This structure just described, is known as the "gate" through which the film passes during the projection of the characters on said film.

Affixed to the wall 18 are two arms, the upper arm 39 and the lower arm 40, these arms being adjustable on screws or supports 41 and 42 respectively. The upper arm 39 carries a 60 pin 43 on which is rotatably mounted a reel

44 from which film 45 is adapted to be unwound or fed. A locking member 46, as is usual, is provided on the pin 43. The film is carried from the reel 44, under a pin 47, and over a sprocket 48 mounted on and affixed 70 to a shaft 49. This sprocket 48 is provided with a plurality of teeth 50, a set of these teeth being provided at each side of said sprocket, and said teeth are adapted to mesh with the perforations 51 in each side of the 75 strip of film 45, thus providing a positive feed for said film. The film is then led upwardly, over the housing 21, and is fed downwardly through the gate. The spring controlled, pivoted plate may be swung open for 80 this operation, if desired. In order to provide for the intermittent feeding of the film through the gate, and prevent undue strains on the film, a free loop 52 is left above the gate. The spring 32 will insure that the film 85 is maintained in a flat, smooth position over the aperture 23. From the bottom of the gate the film is conducted over a sprocket 53 which is mounted on and secured to a shaft 54. The teeth 55 of the sprocket 53 will engage the 90 perforations 51 in the film, and thence the film is conducted back to the sprocket 48, and thereunder, the teeth 50 again holding the perforations 51 and feeding the film to the left, as shown in Fig. 3. A free loop 56 is 95 provided, between the sprocket 53 and sprocket 48, to prevent injury to the film from the pull of the sprocket 48. From its position beneath the sprocket 48 the film is then conducted over the pin 60 to the reel 57 100 mounted on a pin 58, said reel being held in position by a locking arm 59.

In order to provide means to hold the film against the sprocket 48 to insure meshing of the teeth 50 with the perforations 51 in the 105 film, I pivotally mount, on the pins 47 and 60, frames 61 and 62 respectively, the upper frame 61 carrying a roller 63 having a pair of bifurcations therein to accommodate the teeth 50, while at the same time holding the film 110 45 in close contact with the sprocket 48. The lower frame 62 carries a similar bifurcated roller 64 to hold the film against the sprocket 48 on its return passage. A spring 65 is connected to the outer ends of the two frames 115 61 and 62, maintaining a constant pressure on the rolls 63 and 64.

To hold the film against the sprocket 53, I 120 may utilize a similar device to the frames 61 or 62, but preferably I utilize my novel film holding means herein illustrated. This comprises a frame 66 pivotally mounted on the pin or shaft 67, the spring 68 normally forcing the end of the frame which is under the sprocket 53 upwardly, and on said end of the frame I pivotally mount, on the pin 69 a shoe 70, an aperture 71 being provided through the shoe 70 to accommodate said pin. Projecting upwardly from the shoe 70 are two 125 pairs of webs or yokes 72 and 73 having con- 130

caved surfaces 74 and 75, into which concavities the sprocket 53 will fit, the spaces between the pairs of webs 72 and 73 receiving the teeth 55, the concaved surfaces 74 and 75 only bearing against the film closely adjacent to the lines of perforations 51, thus leaving the center of the film free, with no pressure thereon. This particular form of film holding device is extremely efficient and satisfactory, engaging the film over a large portion of the circumference of the sprocket 53, and I believe is novel with me. If desired, also, in place of the rolls 63 and 64, I may utilize the structure just described as the film holding means for the sprocket 48.

The shaft 49 is the main drive shaft of the projector, and on the outer end of this shaft is affixed a handle 76, a screw 77 preventing slippage of the handle on said shaft. The shaft 49 extends through a boss 78 on the wall 18, and through said wall, having affixed on its outer end a gear 79, the shaft being enlarged or headed as at 80 to retain said gear in place. The gear 79 meshes with a pinion 81 on the shaft 82, said shaft being mounted at one end in the wall 18 and at its other end in the raised boss or arm 83. Mounted on the shaft 82 also is a driving wheel 84 having thereon a pin or roller 85, and a circular boss 86, said boss being cut away as at 87 to provide a clearance for the projecting arms of the driven or star wheel 88 mounted on the shaft 54. These wheels 84 and 88 comprise, with the other features thereof to be described, my novel Geneva movement.

Provided in the wheel 88 are four curved slots or cam paths 90. The convex surface 91 of the boss 86 engages the concave surface 92 between each pair of slots before the driving pin 85 is disengaged from the driven wheel 88, thus preventing the latter from rotating while the pin is moving around to engage the next successive slot. As the driving wheel 84 is moving in the direction of the arrow, Fig. 5, it will be appreciated that on entering any slot 90, said pin first engages the curved edge 93 of the slot 90, and, because of the curve of said edge, will not cause the sharp metallic click which has heretofore been present in this type of movement when utilizing radial slots. Thus, my novel construction will enable the driving pin 85 to impart to the wheel 88 a relatively slow start and a smooth acceleration, which start and acceleration are imparted, through the shaft 54, to the sprocket 53, and hence to the film 45, thus preventing injury or damage to the film through too quick a start, or jerk.

A further advantage of my improved Geneva movement is that I may construct the boss 86 and driven wheel 88 in the ratio of five to one or six to one, if desired, which thus increases the time that the film is idle as compared to the time that it is in motion, thus resulting in high speed with smooth

silent action, instead of noisy, jerky action.

I also preferably mount the shaft 54 in an aperture or bore 94 formed eccentrically in the sleeve 95, which sleeve has a reduced portion 96 extending through the wall 18 and boss 97, and on the sleeve 95 I affix a lever or operating device 98, manipulation of the lever 98 rotating the sleeve 95 and hence the shaft 54, bringing the driven wheel 88 into closer contact with the boss 86, or moving it to a greater distance from said boss, as desired, thus providing a wide range of adjustment. Thus I am allowed to compensate for wear on the convex or concentric edge or face 91 and on the concaved surfaces 92, in a simple manner. Such variation of the position of the shaft 54 will of course slightly alter the position of the sprocket 53, but as the shoe 70 is pivoted in its frame, this shoe will follow any altered or adjusted position of said sprocket, and will still perform its film holding function with equal efficiency. In order to hold the sleeve 95 in adjusted position, I provide a set screw 99 extending through the boss 97 and engaging the reduced portion 96 of the sleeve 95, firmly holding the same.

Mounted on the shaft 82 also is a shutter 100 interposed between the aperture 17 in the lamp house 15 and the condenser lens 19, this shutter having a larger shutter vane 101 and two smaller flicker vanes 102, the function of these flicker vanes being well understood in the art and no detailed description thereof being requisite. The shutter vane 101 is adapted to intercept the light from the aperture 17 during the moment that the film is being fed past the apertures 23 and 24. Due to my improved Geneva movement, above described, I am enabled to reduce the size of these vanes to a considerable extent, which represents a further advantage in this art. In order that the shutter 100 may rotate smoothly, I provide the same with a hub 103 and collar 104, fixed to the shaft 82 by a set screw 105 or the like, thus affording a broad bearing surface for the shutter element.

It is necessary, of course, to provide means to insure rewinding of the film 45 on the reel 57, and I accomplish this by mounting on the shaft 49 a grooved disc 106, and on the shaft or pin 58, is another grooved disc 107, and running in the grooves of these two discs is a spring belt or drive 108, which form of drive insures against too-tight winding of the film on said reel 57, slippage of the spring 108 occurring when tension is placed thereon by the film 45.

The lens barrel 27 is mounted in the flange or arm 109 of the wall 18, and is slidable therein, being secured in adjusted or focused position by a set screw 110.

When assembling the gear 79 and grooved disc 106, I preferably unite these two articles, together with a spacing washer 111, by means

of pins 112, position the same against the wall 18, and then insert the headed shaft 49. This method of assembly is optional and is illustrated herein as being a simple method of construction.

The operation of my novel projector is simple, and will be readily understood, being briefly summarized as follows:

The operator places the reel 44 on the pin 43, then conducts the film under the pin 47 and over the sprocket 48, meshing the teeth 50 with the perforations 51 in the film, the roller 63 holding the film firmly against the sprocket. Thence the film is led upwardly over the reflector housing 21 in a free loop 52 and downwardly through the gate, the operator opening the gate by pressing the plate 26 against the tension of the spring 38.

The film is then conducted downwardly under the sprocket 53, the teeth 55 meshing with the perforations 51. Thence the film is led under the sprocket 48, leaving the free loop 56, the roller 64 holding the film against the under side of the sprocket, and thence over the pin 60 to the reel 57. The projector is now ready to operate, and rotation of the handle 76 will cause rotation of the gear 79 and pinion 81. Rotation of the pinion will also cause rotation of the driving wheel 84 of the Geneva movement, which in turn will control the rotation of the star or driven wheel 88 and shaft 54, together with the sprocket 53, in an intermittent movement, as above explained.

Simultaneously the shutter 100 will be operated in synchronism with the feeding of the film through the gate, shutting off the light at the time of feeding of the film, as is usual. The projected film will be rewound on the reel 57 through the medium of the spring belt or drive 108, which will also insure against too-tight winding of the film.

Due to the efficiency of my novel Geneva movement, injury to the film through jerking or the like is eliminated, and the projector illustrated and described herein will function smoothly and efficiently, at the high rate of speed required for these projectors.

When wear has occurred in the Geneva movement, manipulation of the lever 98 controlling the eccentric sleeve 96 will adjust the relation of the wheels 84 and 88.

I believe that my projector, as described herein is novel, and have therefore claimed the same broadly herein.

The film holding mechanism, as particularly illustrated in Figs. 3 and 10 is also believed to be novel, and claim to the same has been included in this application.

While I have necessarily described my present invention somewhat in detail, it will be appreciated that I may vary the size, shape and arrangement of parts within reasonably wide limits without departing from the spirit of the invention.

My invention is further described and defined in the form of claim as follows:

In a machine of the kind described, a film holding reel, a gate comprising a pair of walls having aligned apertures therein, means to feed said film past said apertures, a spring plate positioned between said walls and fixed to one of said walls, said plate having a recess therein aligned with said apertures, and a pair of legs projecting laterally from said spring plate adjacent to the open end of said recess, said legs spanning the space between said walls and bearing against the inner surface of one of said walls to provide an increased pressure of said spring plate against the inner surface of the other of said walls, said legs having upturned ends to provide increased bearing of said legs against the inner surface of the first said wall.

In testimony whereof, I have signed my name to this specification.

ROYAL A. CLAPP.
